ABSTRACT OF THE DISCLOSURE

Container, with closure reclosably held mechanically, is sealed by internal band readily ruptured by release of closure.

This invention relates to containers, especially cans and the like, which may be thoroughly and effectively sealed for shipping and storage of the contents and yet which may be readily opened manually, all without special tools or appliances and without rupture of any external part of the container structure. Indeed, the resistance to rupturing the seal may be so slight that one reason for departing from the objective of eliminating any evident external removable means is to advise the ultimate user with a printed peelable tape that the container is internally sealed and will remain so as long as the external seal is unruptured.

It has long been recognized that many products are purchased for their convenience to the ultimate user but such convenience is defeated if the necessary packaging can only be opened with separate or special tools. In fact, even if the packaging requires no such accessories but does require slightly complex or special and unique manipulations, the packaging does not provide the convenience requisite for products promoted as "convenience" items. Still further, the packaging must be "safe," not only to protect the contents but also unlikely to injure the user during or after it is opened.

It is an object of this invention to provide packaging which is not only suitable for so-called "convenience" goods but which, while providing thorough and effective sealing, is so readily opened and closed that it can raise to the status of "convenience" items, some products which heretofore have been packaged in sealed containers which required separate opening accessories. It is a particular object of this invention to provide sealed packaging means which may be opened (and reclosed without, of course, resealing) without discernible effort or special manipulations which the user may consciously or unconsciously attribute to an un-sealing function over and beyond a simple and natural operation of untwisting a lid or top. No externally evident tapes, keys, lift-rings, or pull tabs are required for opening.

Other objects and advantages of this invention will be apparent from the following specification, claims, and drawings, in which:

FIGURE 1 is a vertical cross-section of the upper portion of a can provided with a shoulder closure cap sealed according to this invention.

FIG. 2 is a fragmentary detail of a cross-section similar to FIG. 1, but showing an alternate form of an internal seal.

FIG. 3 is a view similar to FIG. 2 showing another form of seal.

FIG. 4 is also a view similar to FIG. 2 but showing a still different form of seal.

FIG. 5 is an enlarged detail of a sealing strip such as shown in FIG. 1 in which the strip is a laminate of at least two plies.

FIG. 6 is a view similar to FIGS. 2 to 4, but showing

2

the application of a sealing strip as shown in FIG. 1 to a different form of cover.

FIG. 7 is a view similar to FIG. 6 but showing the use of a sealing strip similar to that in FIG. 3.

FIG. 8 is a view similar to FIGS. 2 to 4, but showing a sealing strip formed in situ.

FIG. 9 is a view similar to FIG. 8, but showing the use with a container closure of the type shown in FIGS. 6 and 7 of a sealing strip formed in situ.

It is to be understood that all of the above described views of the drawings are schematic to a substantial degree in that the thickness and contours of the elements and spacings therebetween are exaggerated and distorted and minor or non-essential details have been omitted, all for the purpose of improving the clarity of illustration of this invention is its various embodiments.

Referring to FIG. 1, a cylindrical can body 10 is closed by a cover 11 having a depending rim comprising an upper shoulder portion 12 and an enlarged lower portion 13 provided with suitable means for mechanically but releasably (upon rotation) engaging the upper open end of the can body 10. The internal diameter of the shoulder 12 is substantially equal to the internal diameter of the can body and the general internal diameter of the lower rim 13 is only sufficiently larger than the outside diameter of the can body to provide the tolerance for a fairly close but non-binding sliding fit. The juncture of the shoulder and lower rim portions 12 and 13 thus provides a seal for the upper and usually beaded edge of the can body. The particular means disclosed for mechanically engaging the cover 11 on the can body 10 so that it can be released upon rotation—and re-engaged by rotation—are simply short mating threads 14 and 15 rolled into the cover rim and can body, respectively, to provide an interrupted screw connection which can quickly and simply allow the cover and can body to be disengaged or engaged by a relatively small twist. Various other means for effecting similar mechanical engagement may be employed, such as various forms of the so-called bayonet type of lock, internally formed spring-latching or "speed-nut" type of connections, as well as a screw connection which requires several turns to effect engagement or dis-engagement. In general, the short interrupted screw connection is preferred, since it operates quickly, provides the relative rotational movement preferred for the invention, and a short twist to remove any cylindrical lid or cover is practically an instinctive movement of the user, even when removing covers having a loose friction fit. Still another advantage of the screw connection is that it permits the shoulder 12 to be pulled into an internally jamming engagement with the upper edge of the can body whereby the frictional engagement of the cover 11 on the can body 10 can be carefully torqued to provide a secure fit and interlock of the cover on the can body during normal handling and shipping and yet not so tight as to require more than an instinctive firm manual twist to break the internal static frictional engagement of the cover 11 and can body 10.

After the cover 11 has been releasably locked as described above on the can body 10, which is still open at its bottom, the cover is held upon the can body sufficiently securely to withstand any shifting of the contents or of the cover during normal handling and shipping. By no means, however, would the joint between the body and cover be effectively sealed against leakage into or out of the container. This sealing is accomplished by an internal sealing band shown in its simplest form as the band 20 in FIG. 1. The particular material of the band 20 is usually and primarily determined by the nature of the contents to be packaged. Thus, the band 20, as a single ply tape, may be of metal foil, usually a soft aluminum foil, or a flexible organic film such as, for example, a

polyester or fluorocarbon film selected for its dimensional stability and usual inertness to most types of contents which may be packaged.

The band 20 is usually held in a sealing position by a band of adhesive 21 between the sealing band 20 and the shoulder portion 12 of the cover 11 and by a second band of adhesive 22 between the band 20 and the upper portion of the can body 10, the band 20 usually being secured by a longitudinal lap seam 23 unless it is actually a band cut from a seamless tubing of the selected material. If a longitudinal seam 23 is employed, it may be formed as a length of tape is laid internally over the joint between the body 10 and cover 20. However, because of the close tolerances to which the internal diameter of the shoulder 12 and body 10 are usually held and the better control which can be exercised when the band material is formed externally, the band 20 is usually formed externally on a mandrel as tubing which, with the adhesive 21 and 22 applied, is then cut to band lengths. A band length is then picked up on an expandable mandrel by which the band is inserted to the closed end of the can body and then positioned as shown in FIG. 1 by expanding the positioning mandrel. Whether the seam 23 of such a band is axially longitudinal, as shown in FIG. 1 or is spiral depends upon the type of tube-forming equipment employed when the band is formed of a sheet material.

Just as the specific material of the sealing band 20 is a matter of selection determined by its relative inertness to the contents to be packaged, so the specific adhesive of the bands 21 and 22 is likewise determined by the nature of the contents to be packaged. The adhesive may be a solvent activated type but, because of the effect which slowly released solvents may have on the taste of items packaged for human consumption, the adhesive is usually a hot-melt wax and/or resin or other type activated by heat and/or pressure or an epoxy resin or other condensation product and which thereafter is inert with respect to the packaged contents.

Although the bands of adhesive 21 and 22 may, in some instances, be combined as a single band extending over the joint between the body 10 and cover 11, the two spaced bands are preferably employed for two reasons: First, unless preventive measures are taken, seepage of adhesive into the joint as the adhesive is activated may well, for all practical purposes, permanently seal the cover 11 to the body 10, due to the enormous film strength of many adhesives. Second, the sealing band should be readily rupturable at a pre-determined location, a result which is difficult to obtain if the entire surface of the sealing strip is secured to the container. When the sealing band 20 is a single ply, as shown in FIG. 1, the absence of adhesive adjacent the joint between cover and body insures that the band will rupture in shear adjacent the joint when the container is opened by twisting off the cover 11. To locate such rupture more precisely, the band 20 is provided with a score line 24 just above the lower band of adhesive 22. Since the material of the sealing strip is frequently readily deformable, in the absence of such a score line, the sealing band 20 will otherwise usually shear with an unattractive, ragged edge adjacent the seat of the shoulder 12 on the upper edge of the can body where the band 20 may be slightly weakened by being stretched into the joint between the can elements, as illustrated. The depth of the score line 24 and the gauge of the band 20 are adjusted with respect to each other to preferentially weaken the band at the location of the score line 24 without destroying the sealing strength of the band. Alternatively to providing a score line or other weakening line to effect rupture of the sealing band 20 at a predetermined location, one of the adhesive bands, but preferably 22, may be narrowed, or it may be of an adhesive selected to peel more readily from the can wall, whereby the sealing band is effectively ruptured, not by rupture of its material but of its adhesive strip, when the container is opened by twisting off the cover 11.

As indicated above, it is preferable to have the sealing band 20 rupture below the upper edge of the can body 10 so that it will be carried as a depending skirt with and into the depending rim of the cover 11 when the cover is twisted off. This not only locates any relatively unattractive torn edge of the sealing band below the formed upper edge of the can body, but particularly if the band 20 is of easily and permanently deformable material, such as soft aluminum foil, the twisting off of the cover 11 will tend to stretch the bottom of the band 20. Thus the portion of the band carried as a skirt with the cover 11 will tend to be flared outwardly against the inside of the depending rim portion 13. This is desirable since the skirt formed by the band 20 will tend to be compressed in the seat provided by the shoulder 12 when the container is reclosed, thereby functioning as a compressible packaging which aids in sealing the reclosed container.

The alternative fragmentarily shown in FIG. 2 differs from the structure shown in FIG. 1 in that the sealing band 120 is employed instead of the band 20; the other similar elements being identified by similar reference numbers. Instead of being a single ply, as the band 20 in FIG. 1, the sealing band 120 is provided with a cuff 121 (which may be folded outwardly as well as inwardly, as shown in FIG. 2). The cuff 121 extends downwardly to nearly the lower adhesive band 22 and is laminated to the remainder of the band 120 by solvent or heat fusion, or by use of a suitable adhesive (not shown). The purpose and advantage of this slightly more complex sealing band is that it permits thin gauge foils or films to be employed, providing for ample strength of the seal at the joint between the body 10 and cover 11 due to the double ply at that location. The single ply between the upper edge of the adhesive band and the lower edge of the laminated cuff constitutes an area of weakness for subsequent rupture. This is due not only to the single ply but the consequent concentration of torque forces in this single ply area.

FIG. 3 shows another variation of a sealing band in a container as otherwise described and shown in FIG. 1, using corresponding reference numbers for otherwise corresponding parts. As shown in FIG. 3, a sealing band 220 is provided with an outwardly folded upper cuff 221 laminated to the body of the band 220 (in a manner similar to that by which the inwardly folded cuff 121 is laminated in the band 120). A second lower cuff 222 extends to or slightly above the lower adhesive band 22 and is similarly laminated to the body of the band 220. This permits an even more sharply definable rupturable area 223, the strength or shear of which is closely predictable because of the normally close gauge control obtained in the production of the foil or film used for the sealing band.

FIG. 4 shows a still further alternative form of sealing band which may be used in a container as otherwise described and shown in FIG. 1, using like reference numbers for like members. As shown, the band 320 is provided with a cuff 321 extending for the full depth of the band 320 and laminated to the body of the band, as by a layer of adhesive 323. As shown, the cuff 321 is folded inwardly but may be folded outwardly. Whether the cuff is folded inwardly as shown (or outwardly to encase the adhesive), the band is provided with a lower cuff 322 folded outwardly of the plies in the band. This cuff 322, which is adhered by the lower adhesive band 22 to the can body 10, is purposely not adhered to the adjacent ply in the band 320. This permits the lower outer fold 324, which may be pre-weakened by a score line (not shown) at the fold, to function as the weakened area for rupture of the sealing band 320. The advantage of this construction is not only that it provides a band which is strong throughout its depth against any pressure differential across the joint between the can body and cover, but the torn edge will be below the upper cut edge, which latter edge will be the one first seen by a user after the container is opened.

As implicit in the foregoing showings of the various seal-

ing bands as being made of single ply material, the material may be a laminate of various combinations of films and foils, including, if such be needed, laminates of the same material and those using layers of paper or like fibrous-reinforcing material. In most instances, however, a two-ply material is employed, such as, in the band 420 fragmentarily shown in FIG. 5, an inner lamina of film 421 which is wholly inert to contents to be packaged, and an outer lamina of metal foil 422 which functions as a barrier to vapors and gases to which the film 421 may be somewhat permeable. Another advantage of such laminated sealing band material is that it permits the longitudinal seam 423 of the film to be offset from the seam 424 in the foil whereby a stepped or scarfed seam is obtained; the "bump" of a lap seam 23, as shown in FIG. 1, is thereby avoided. A rupture line 425 is provided by scoring the film 421.

The advantage of the shouldered cover 11 as shown in FIGS. 1 to 4 is that it permits the sealing bands to be essentially cylindrical. Many stock screw-top covers 511, as shown in FIG. 6, however, simply have a depending short flanged rim 513 in which the closure screw-threads 514 are formed so as to draw up the upper edge of a can body 10, having formed therein the threads 15, so that it is seated against the generally planar portion of the cover 25 511, as shown, or in an annular channel formed therein. Rather than being sealed by compaction of the usual jar or packing ring compressed between such a lid and the upper edge of the can body, such a cover and can body may be sealed by an internal sealing band 520. The sealing band 520 may essentially duplicate the band 20, shown in FIG. 1, and may be adhered adjacent the upper edge of the can body 10 by a lower adhesive band 22. However, as shown in FIG. 6, the upper portion of the sealing band 30 35 40 45 50 55 60 65 70 75 520 is folded inwardly and adhered to the planar portion of the cover 511 by a ring of adhesive 521. This necessitates the formation of miter folds 522, which need not interfere with the sealing function of the band 520 due to the flow of the adhesive 521 into such folds when the adhesive is activated. Due to the gap between the adhesive band 22 and the ring 521, the sealing band will rupture in its unattached area when the cover is twisted off. To further localize the area, a score line 523 may be employed.

By so infolding the upper margin of a sealing band, any sealing band exemplified by those shown in FIGS. 1 to 4 for use on cans closed by a shouldered cover 11 may be used for cans closed by a cover of the type exemplified by the cover 511 in FIG. 6. Thus, in FIG. 7, with otherwise like parts given like reference numbers as used in FIG. 6, a band 620, similar to that shown in FIG. 3 (except that the cuffs are folded inwardly), is employed.

In any embodiment employing an un-shouldered cover flange, the need for flow of the adhesive, shown as 521, into the miter folds of the upper margin of the sealing band 55 necessitates that measures be taken to prevent such flow of adhesive from also entering the joint between the can body and cover as the adhesive is activated; otherwise the activation could well permanently seal the cover to the body. One simple expedient is to first coat the edge of the can body with a liquid or gel-like material which is immiscible with and/or repellent of the adhesive in the ring 521. Thus, many of the pressure-sensitive or heat and pressure sensitive adhesives are, in their activated condition, essentially hydrophilic. Thus, before applying the cover and the sealing band, a single coating of the edge of the can body with a hydrocarbon oil, petrolatum, or water-insoluble soap or like hydrophobic material will protect the joint from being filled with the adhesive. If the adhesive is essentially hydrophobic at the time it is activated, a suitable hydrophilic material is pre-applied to the joint. Alternatively, a single gasket of paper or the like may be used to block the joint. Still further one may employ thixotropic adhesives which cannot flow into small crevices such as the joint.

The foregoing expedient of preventing flow into the can and cover joints for the embodiment shown in FIGS. 6 and 7 permits plastic or like films to be formed in situ to function as a sealing band. Thus, in FIG. 8, a can body 10 having a shouldered cover 11, as shown in FIGS. 1 to 4, has a repellent material pre-filled in the joint between the body and cover and then a sealing band 720 of suitable film-forming material is made in situ by applying it from a spray gun, roller, or fountain brush. The film-forming material may be applied in liquid form as a solvent-solution, latex, plastisol, or simply as a hot-melt liquid. The repulsion between the pre-filled material in the joint and the material from which the sealing band is formed usually causes a thinner section of the film adjacent the joint, which section thereafter functions as a score line when the cover is twisted off. FIG. 9 shows the same expedient applied as in FIG. 8, except that a shoulderless cover 511, as in FIGS. 6 and 7, has been employed and the sealing band 820 extends, of course, onto the planar portion of the cover. Alternatively, the band may be cut from a tube of thermoplastic resin; after insertion by a suitable mandrel and with heating, the band may be fused, without the aid of adhesives, to the inner walls of the container so as to bridge the joint between the cover and can body.

It is to be understood, of course, that in all of the foregoing embodiments, the can body is open at its lower end to permit the cover to be sealed by a suitable sealing band. Thereafter the container is filled through the bottom, with the sealed cover inverted, and the container may then be closed by any suitable permanent bottom closure. The requirement that the rupturable seal be applied internally before filling and closing does not, however, exclude the use of this invention for sealing jars or other open containers in which the bottom is necessarily formed integral with the side walls or body. In such case, a cylindrical band having screw threads or like mechanical attaching means formed therein is first threaded on the jar body and sealed with a sealing band. After filling, the cylindrical band is then crimped or otherwise united with a generally planar closure so that the cylindrical band becomes, in effect, the dependent threaded rim shown in FIGS. 1 to 4 and 6 to 9.

It should be apparent from the foregoing that the essential and underlying principle of this invention is to separate the sealing function from the mechanical closing function and thereby utilize the mechanical strength of the can and cover to perform the closing function and a separate sealing band to perform the sealing function. Although the sealing band is amply strong for its intended function, by utilizing the relatively weak strength in shear the normal initial twist to unlock the cover may, with no discernible extra effort, disrupt the seal.

What is claimed is:

1. In a container, a container body having an upper planar edge defining an opening and one portion of releasable mechanical locking means carried externally on said container body adjacent said edge, a cover closing said opening and having a depending rim and the remainder of said mechanical locking means carried on said rim, said locking means being engaged and disengaged by rotational movement of said one portion with respect to said remaining mating portion, an internal sealing band of flexible rupturable material bridging and secured over the internal joint between said cover and the said edge of said container body when said locking means are engaged, said material being selected to be substantially inert to the contents intended to be packaged in said container and to have insufficient elasticity in the portion bridging said joint to withstand the lateral displacement when said body and cover are rotated with respect to each other to release said locking means, whereby said band seals said joint when applied after said locking means are engaged and release of said locking means ruptures said seal.

2. A sealed container as defined in claim 1, in which said band is formed with a line of weakness to localize the rupture of said seal.

3. A sealed container as defined in claim 2, in which a material essentially blocking a sealing material of said band is located in said joint.

4. A sealed container as defined in claim 3, in which the sealing material of said band includes an adhesive for a sheet material in said band, a liquid film-forming material by which said band may be formed in situ, or a thermoadhesive film.

5. A sealed container as defined in claim 2, in which material of the sealing band includes a sheet material comprised of foil, film, or laminate thereof.

6. A sealed container as defined in claim 5, in which said band is sealed to said container body below said edge and to said cover by spaced bands of adhesive leaving the sheet material of said band otherwise free to move with respect to said joint.

7. A sealed container as defined in claim 6, in which said band includes a cuff of said sheet material extending to the edge of the band of adhesive securing said band to said body, said cuff being joined to said band to provide a line of weakness for rupturing near said adhesive band.

8. A sealed container as defined in claim 7, in which said band includes a second cuff of said sheet material extending toward the edge of said first cuff, whereby the gap between the edges of said first and second cuffs defines a localized area for rupture.

9. A container as defined in claim 7, in which a cuff extends for the depth of the band and is laminated to provide a two-ply layer and a second cuff is folded outwardly

of said band but is unattached thereto except at said fold, whereby when said outer cuff is adhered to said container at one side of said joint and the remainder of said band is adhered to said container at the other side of said joint, relative movement of said body and cover to release said locking means ruptures said band at the fold between said outer cuff and the balance of said band.

10. The method of sealing a container comprising the steps of releasably locking a cover member on one open end of a container body, applying a rupturable band over the joint between said cover and body, said band being secured to each except in the area of said joint and fitting the interior of said container so as to bridge the joint with insufficient material to permit the cover to be unlocked without rupturing said band, and thereafter filling and closing said container with contents to be packaged.

11. The method as defined in claim 10 in which said container body is essentially cylindrical and open at opposite ends and the step of filling contents in said container after internally sealing said releasably locked cover is performed through the opposite end, which opposite end is thereafter sealed.
